Primary Examiner—Wallace R. Burke*Assistant Examiner*—Lavone D. Tabor*Attorney, Agent, or Firm*—Cushman, Darby & Cushman[57] **CLAIM**

The ornamental design for a kitchen sink scraper or similar article, as shown and described.

DESCRIPTION

FIG. 1 is a front elevational view of a kitchen sink scraper or similar article showing my new design;

FIG. 2 is a perspective view thereof from the rear, bottom and left side, on a smaller scale; and,

FIG. 3 is a left side elevational view thereof, on a larger scale, the right side being a mirror image thereof.

FIG. 1

FIG. 2

FIG. 3
